UNITED STATES PATENT OFFICE.

JUDAII POLAK, OF NEW YORK, N. Y.

DESIGN FOR A SCARF-PIN.

SPECIFICATION forming part of Design No. 29,402, dated September 27, 1898.

Application filed May 10, 1898. Serial No. 680,321. Term of patent 3½ years.

To all whom it may concern:

Be it known that I, JUDAH POLAK, a citizen of the United States, residing at New York, in the county of New York and State of New York, have invented and produced a new and original Design for Scarf-Pins, of which the following is a specification, reference being had to the accompanying drawings, forming part thereof, in which—

Figure 1 is a view in elevation of my newly-designed scarf-pin, and Fig. 2 a section thereof on the line 2 2.

The object of my invention is to provide a scarf-pin which represents a flag above a top; and, as shown in the drawings, my newly-designed scarf-pin consists of the representation of a flag D, the upper and lower edges of which, together with the stripes thereof, are formed to represent convolutions or wave-shaped undulations, said flag being provided with a

flagstaff C, the lower end of which is formed into a pin A, and said staff being provided at its upper end with a knob or head E and immediately below the flag with an enlarged portion or body B, which represents a top. 25

My newly-designed scarf-pin may be composed of any desired material.

Having fully described my invention, I claim as new and desire to secure by Letters Patent—

The design for a scarf-pin herein shown and described.

In testimony that I claim the foregoing as my invention I have signed my name, in presence of the subscribing witnesses, this 9th day 35 of May, 1898.

JUDAII POLAK.
